US0D1015151S

(12) **United States Design Patent** (10) **Patent No.:** **US D1,015,151 S**
(45) **Date of Patent:** **** Feb. 20, 2024**

(54) **FOOD CONTAINER LID**

- (71) Applicant: **Constantia Teich GmbH**, Weinburg (AT)
- (72) Inventors: **Rudolf-Peter Stieböck**, St. Pölten (AT); **Martin Kornfeld**, Klosterneuburg (AT); **Adolf Schedl**, Lilienfeld (AT); **Ewald Köberl**, Kilb (AT)
- (73) Assignee: **Constantia Teich GmbH**, Weinburg (AT)
- (**) Term: **15 Years**
- (21) Appl. No.: **29/887,494**
- (22) Filed: **Mar. 21, 2023**

Related U.S. Application Data

- (62) Division of application No. 29/715,134, filed on Nov. 27, 2019, now Pat. No. Des. 1,003,713.

(57) **CLAIM**

The ornamental design for a food container lid, as shown and described.

DESCRIPTION

FIG. 1 is a top front right isometric view of a food container lid showing the new design;

FIG. 2 is a bottom rear left isometric view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and

FIG. 8 is a top view thereof; and,

FIG. 9 is an environmental top front right isometric view thereof, shown attached to a food container body and with the top layer of the food container lid shown partially peeled away from the lower layer of the food container lid.

The broken lines are shown for the purpose of illustrating environmental subject matter of an exemplary food container and form no part of the claimed design.

1 Claim, 4 Drawing Sheets
